CLAIM

The ornamental design for the desk lamp, as shown and described.

DESCRIPTION

FIG. 1 is a front elevation view of the desk lamp showing my new design;

FIG. 2 is a back elevation view thereof;

FIG. 3 is a left elevation view thereof;

FIG. 4 is a right elevation view thereof;

FIG. 5 is a top elevation view thereof;

FIG. 6 is a bottom elevation view thereof; and,

FIG. 7 is a perspective view thereof.

The broken lines illustrate portions of the desk lamp that form no part of the claimed design.
